FABRIC

Henri Barbet, Scarsdale, N. Y., assignor to Albert Godde, Bedin, Inc., New York, N. Y., a corporation of New York

Application April 22, 1933, Serial No. 667,383

4 Claims. (Cl. 139—384)

The present invention relates to a new and improved fabric and it particularly relates to a fabric with a pleated or tucked effect formed simultaneously with the fabric as an integral part thereof.

In the past, when forming pleated or tucked effects, the fabric was first woven or formed in flat condition and then by a subsequent sewing operation by hand or with a special machine, the tucks or pleats were formed. Tucks or pleats formed by these additional operations by folding or gathering up of the woven or other fabric usually are not regular, are at unequal distances, do not closely conform to the straight of the material, and do not lay satisfactorily, but tend to give an undulatory appearance, necessitating pressing and other flattening operations so that the fabric will have a satisfactory appearance. Moreover, the fabric or garment made of it, tends to become ruffled and mussed easily and it must be frequently pressed and again finished.

Even when the fabrics are most carefully pressed and finished they tend to bulge or undulate even after slight usage. The thread or extra binding which must be utilized to give the tucked or pleated effect detracts from the artistic appearance of the fabric, and, moreover, tends to give it a seamed effect.

The object of this invention is to provide a fabric and process for making the same, in which the pleat or tuck is formed integrally with the fabric itself, preferably during the weaving operation, which fabric will have a superior pleated or tucked effect, will be more dressy in appearance and will not tend to readily crumple or fall out of shape during usage.

Another object is to provide a pleated or tucked fabric of altogether new appearance which will be relatively inexpensive and which will not necessitate the expense of extra tucking or pleating operations after weaving.

Other objects will be obvious and will appear during the course of the following specification.

It has been proposed previously to form pleats in fabrics when the fabrics are woven. But such pleated or tucked constructions have never been found satisfactory because of the tendency of the pleats or tucks to pull out when the fabric was subjected to any longitudinal stretch. To overcome this, attempts were made to provide double fabrics or multiple-ply fabrics, one of which fabrics would not be pleated but would act as a sort of a reinforcement to hold the pleat together. The utilization of multiple-ply fabrics of this character not only resulted in an unsatisfactory appearance, but in addition would not satisfactorily prevent the drawing or pulling out of the pleats or tucks.

A feature in the present invention resides in the construction of a pleat or tuck woven integrally into the fabric in such a manner that the

pleat will retain its shape and will not tend to separate. Although the weave may be constructed in many different fashions in combination with the pleat it has been found particularly satisfactory in assuring permanency of the pleat, and in causing closing of the pleat adjacent its base to provide three Gros de Tours bindings or double groups or pairs of filler or pick threads enclosed in links formed by the warp threads.

In this way assurance is had that the pleat will close at its base and will not have a tendency to open during and after the weaving process.

Although the objects of the present invention may be attained in various ways, one method which has been found satisfactory is to provide two warps to be incorporated in the single pleated or tucked fabric, one warp alone being utilized when the pleats or tucks are being formed and both warps together being combined when the base or background is being formed.

By forming the fabric in this fashion the pleat elements will have a lesser density in warp threads than will the fabric intervening between the pleats or the background, as it may be termed, while the base between the pleats or their terminal edges will be joined together by the remainder of the warp threads, giving reinforced pleated or tucked construction of greatly improved character and of enhanced wearing qualities.

The above and other objects will appear more clearly from the following detailed description, when taken in connection with the accompanying drawings, which illustrate one embodiment of the inventive idea.

In the drawings:

Fig. 1 is a diagrammatic bottom view of a fragmentary portion of the new fabric according to the present invention.

Fig. 2 is a diagrammatic side sectional view of the fragmentary portion of the fabric illustrating the construction thereof.

Fig. 3 is a diagrammatic side view illustrating the weaving operation when the pleat is being formed, and

Fig. 4 is a diagrammatic view illustrating the weaving operation when the background or base between the pleats is being formed.

As illustrated in Figs. 3 and 4, the completed fabric 10 with the pleats or tucks 11 integrally woven thereinto is wound upon the drum 12. The shuttle (not shown) carrying the picks, end, filler or woof threads, is passed through the warp threads at the weaving zone 13. Two sets of warp threads are utilized, one being carried on the drum 14 and the other being carried on the drum 15.

As shown in Figs. 3 and 4, the drum 14 is designed to carry the pleating or tucking warp while the drum 15 is designed to carry the base or background warp.

As diagrammatically illustrated, the heddles 16 carry the base or background warp while the heddles 17 carry the pleating warp. A large number of these heddles, of course, will be utilized, 5 corresponding to the entire width of the warp.

As illustrated, in Fig. 3, when the pleat is being formed the heddles 16 do not operate, but the heddles 17 operate on the pleating warp threads 18 so that the shuttle (not shown) will carry the woof 10 or pick thread only through the pleating warp 18. The background warp 19 may be positioned below the pleating warp 18 during weaving, or it may otherwise be removed from the weaving zone 13.

15 In Fig. 4 when the background or fabric between the pleats 11 is being formed it will be noted that the heddles 16 and 17 are both operated in unison so that the background warp 19 as well as the pleating warp 18 will be incorporated 20 into the fabric.

To achieve this result attachments (not forming a part of this invention) may be used in connection with the loom which will have the effect of releasing the pleating warp at the desired intervals so that the pleat will be woven for a desirable number of picks. By these attachments, it is possible to regulate the width and depth of the pleat. After such release, the two warps may be caused to work together to 30 form the ground between the spaced pleats or tucks. A similar effect may also be obtained by releasing the front roller after the weaving of the pleat.

It is, of course, to be understood that different 35 types of threads may be utilized for the pleating warp 18 and for the background warp 19 and also for the pleating pick threads 25 and for the background pick threads 26, (Fig. 2).

It is evident, therefore, that the most novel 40 and pleated effects may be obtained, in which, although the pleat is a unitary part of the fabric, it has a novel and distinctive appearance and has a distinct decorative effect, as applied to the fabric, in addition to the usual pleated and tucked 45 appearance.

The fabric as formed is best shown upon Figs. 1 and 2. In Figs. 1 and 2 the pleating warp threads 18 and the ground warp threads 19 are shown woven together to form the ground portions 10 and the pleats 11. The pick threads for the pleat are indicated at 25, while the pick threads for the ground are indicated at 26.

It will be noted in Fig. 2 that the ground warp threads 19 extend across the base of the pleat 11 and reinforce the same, while the pleat forming warp threads 18 extend around the pleat 11, as a result of which greater length of the pleating warp is utilized than of the ground warp. The pick threads 25 in the pleat 11 may be of the same construction as the pick threads 26 in the ground, or different types of threads may be utilized.

The pleats formed are regular, are of equal 65 space and are rigorously held upon the straight of the material. The necessity for extra pleating or tucking operations either by hand or by a special machine are altogether eliminated. A seaming or sewing thread appearance is altogether absent and a very even crosswise pleated 70 effect is attained. The fabric will lay flat and will not undulate or become misshapen like a material pleated after weaving.

Moreover, the pleat will be closed at its base and will not have a tendency to open during and after the weaving process. The weaving including utilization of three Gros de Tours bindings will prevent shifting of the ground in respect to 5 the weave.

What is claimed is:

1. A pleated or tucked fabric in which the pleats or tucks have been woven integrally in the fabric, said pleat or tuck being so woven as to 10 assure perfect closing and shifting, and the filling threads of the ground on either side of said pleat or tuck being held in a double binding in which the warp threads cross outside of the two end filling threads and in which there is no crossing 15 of warp threads between said filling threads, whereby said filling threads will be drawn together upon longitudinal stress of the fabric.

2. A pleated or tucked fabric in which the pleats have been integrally woven into the fabric, two warps being utilized, both being woven in the fabric between the pleats and only one being woven into the pleated portions of the fabric, the base of said pleat being provided with 20 three Gros de Tours bindings, one of said bindings receiving the last threads of the ground on either side of said pleat or tuck, and the other two of said bindings respectively receiving the lowermost filling thread of the pleat or tuck and 25 the last filling thread of the ground, said bindings each enclosing two filler threads in such a manner that the warp threads cross outside of said filler threads and so that said filler threads are not separated by crossing warp threads, whereby 30 said filling threads will be drawn together upon longitudinal stress of the fabric.

3. A pleated or tucked fabric in which the pleats or tucks are woven integrally into the fabric during formation, said fabric including two 40 warps, both of which are woven into the ground or base between the pleats, one of which is woven into the pleat and the other of which extends between the edges of the pleat to reinforce the same, the last filling threads of the ground on either 45 side of said pleat or tuck being contained in a single double binding extending across the base of the pleat or tuck, the warp threads being only crossed outside of said last ground filling threads and there being no crossing warp threads between 50 said filling threads, whereby said filling threads will be drawn together upon longitudinal stress of the fabric.

4. A process of forming integrally pleated or 55 tucked fabrics which comprises providing two warps, one for the pleated and ground effect and an additional warp solely for the ground effect, weaving the first-mentioned warp to form the pleat and then weaving the second warp together with the first-mentioned warp to form the ground, the last filling threads of the ground on either 60 side of said pleat or tuck being contained in a single double binding extending across the base of the pleat or tuck, the warp threads being only crossed outside of said last ground filling threads and there being no crossing warp threads between 65 said filling threads, whereby said filling threads will be drawn together upon longitudinal stress of the fabric.

HENRI BARBET.
